UNITED STATES PATENT OFFICE.

PAUL HANSMANN, OF LONG PRAIRIE, MINNESOTA, ASSIGNOR TO HANSMANN MANUFACTURING COMPANY, OF LONG PRAIRIE, MINNESOTA, A CORPORATION OF MINNESOTA.

ADJUSTABLE STEERING MECHANISM.

1,026,312.

Specification of Letters Patent. Patented May 14, 1912.

Application filed January 17, 1911. Serial No. 603,176.

To all whom it may concern:

Be it known that I, PAUL HANSMANN, a citizen of the United States, residing at Long Prairie, in the county of Todd and 5 State of Minnesota, have invented certain new and useful Improvements in Adjustable Steering Mechanism, of which the following is a specification.

My invention relates to improvements in 10 means for connecting together a plurality of binders or similar vehicles arranged one behind the other wherein the binders may be independently controlled to travel in varying offset paths, its object being particularly to provide a draft connection for a 15 plurality of vehicles as binders, in association with coöperating adjusting mechanism which will hold the successive vehicles in offset paths, the draft connection being so 20 constructed and so connecting the vehicles as to coöperate with the adjusting mechanism in the offsetting of the vehicles.

In the accompanying drawings forming 25 part of this specification, Figure 1 is a perspective view of a binder partly broken away and illustrating in connection therewith my improved connecting means arranged to connect a plurality of binders; Fig. 2 is a plan view of the same; Fig. 3 is 30 a plan view of a plurality of binders connected through the medium of my features of invention; and Fig. 4 is a detail view of the draw bar forming part of my invention.

In the drawings A represents a binder of 35 the usual construction.

B represents a tongue having pivotal support 2 on a cross bar 3. The tongue is adapted to be turned upon its pivot 2 and held in adjusted positions with reference to 40 the cross bar by suitable adjusting mechanism C. The cross bar 3 of each tongue is connected with the free end of the next rear tongue by a draw bar 4. Each draw bar 4 has vertical pivotal connection 5 at one end 45 with the free end of the adjacent tongue B and at its opposite or front end carries a lug 6, said lug being angularly disposed upon said bar for the purpose hereinafter more particularly set forth. The adjacent 50 cross bar 3 is connected with the forward end of said lug by a horizontally disposed pivot 7 and the upper end of said lug is similarly connected by a horizontally disposed pivot 8 with the arm 9 constituting a

part of the framework of the binder. The 55 cross bar as is shown is further connected at one end with the framework of the binder by a hook 10 carried by the cross bar and fastened through an eye 11 upon the binder. The rear portion of the binder may be fastened upon the draw bar as by an eye bolt 12 secured underneath the draw bar and receiving an adjacent portion of the binder framework.

13 represents a hand actuated lever for 65 tilting the forward end of the binder. The lever 13 is shown mounted upon a shaft 14 carrying at its outer end a forwardly extending arm 15. The free end of the arm 15 is pivotally connected by a strap 16 with 70 a bracket 17 extending upwardly and forwardly from the cross bar. By employing a plurality of tongues B equipped with suitable means for securing each at an angle with its cross bar and connecting said 75 tongues with my improved draw bars or equivalent means 4 I am enabled to draw a train of binders or similar vehicles, by suitable motive power, across a field and to independently control each binder to run in 80 desired offset position to cut the required swath. Further, by means of my improved method of attachment of the front end of the binder to the corresponding end of the draw bar and the leverage connection to a 85 point forward of the cross bar I am enabled to independently tilt the forward end of each binder. It will be evident also that any one binder may be easily removed from the train without affecting in any way the 90 operation of the binders in front or at the rear thereof. It will also be evident that a draft member associated with the vehicle and which forms a part of the draft connection for the vehicles, relieves the binder 95 frame from a direct strain in pulling the binders in the rear.

I claim as my invention:

1. Means for connecting vehicles with forwardly extending draft tongues in series 100 and holding them in horizontally offset positions, comprising a draw member supported from one of said vehicles, said draw member forming a connecting link between the draft tongue of said vehicle and the 105 draft tongue of a following vehicle and being adapted for pivotal connection with each of said draft tongues, and means for

maintaining the tongue of said vehicle in position holding the next forward vehicle offset with reference to the next rear vehicle.

2. Means for connecting vehicles in series and holding them in horizontally offset relative positions comprising draw means supported from one vehicle, said draw means at the front of the vehicle being adapted for pivotal connection with the tongue of the vehicle, and at the rear of the vehicle and at a point laterally offset from the connection of said tongue being adapted for similar pivotal connection with the tongue of a following vehicle, and means for maintaining the tongue of each vehicle in position holding the next forward vehicle in offset position with relation to the next rear vehicle.

3. Means for connecting a vehicle in series with other vehicles and holding said vehicles in horizontally offset relative positions, comprising draw means supported from said vehicle and pivotally connected at the front of the vehicle with the vehicle tongue to permit said tongue to swing in vertical and horizontal planes, said draw means at the rear of the vehicle and at a point laterally offset from the pivotal connection with the tongue being adapted for pivotal connection with the free end of the tongue of a following vehicle, means for maintaining said tongues in horizontally adjusted positions to hold the connected vehicles in relatively offset positions, and means for tilting the forward end of the vehicle with relation to said draw means.

4. Means for connecting a vehicle in series with other vehicles and holding said vehicles in horizontally offset relative positions, comprising a draft tongue for said vehicle, means for securing said tongue at an angle with said cross bar, a draw member pivotally connected at one end to said tongue at an angle therewith and adapted for pivotal connec-

tion at its other end with the free end of the tongue of a following vehicle, and means for supporting said draw member from an associated vehicle in alignment with the adjacent cross bar.

5. Means for connecting a vehicle in series with other vehicles and holding said vehicles in horizontally offset relative positions, comprising a draft tongue for said vehicle, a cross bar pivotally supporting said tongue, means for holding said tongue secured at an angle with its supporting cross bar, a draw member having horizontal pivotal connection with said cross bar and positioned at an angle therewith, said draw member being adapted for vertical pivotal connection at its opposite end with the free end of the tongue of a following vehicle, means for removably supporting said draw member from said vehicle with said vehicle in alignment with the adjacent cross bar, and means for tilting the end of said vehicle.

6. Means for connecting a vehicle in series with other vehicles and holding said vehicles in horizontally offset relative positions, comprising a draft tongue for said vehicle, a cross bar pivotally supporting said tongue, means for holding said tongue secured at an angle with said cross bar, a draw portion having horizontal pivotal connection with said cross bar and positioned at an angle therewith, said draw portion being adapted at its opposite end for vertical pivotal connection with the free end of the tongue of a following vehicle, and means for tilting the forward end of said vehicle with reference to the associated cross bar.

In testimony whereof I affix my signature in presence of two witnesses.

PAUL HANSMANN.
